UNITED STATES PATENT OFFICE.

ANDREW J. WIKANDER, OF BROOKLYN, NEW YORK.

AUTOMATIC FEED FOR PORTABLE DRILLS.

Application filed October 3, 1927. Serial No. 223,753.

This invention relates to drills and comprehends an improved drill to take the place of or to be used in lieu of the ordinary ratchet drill which is actuated by rocking 5 movement of a handle.

One of the principal objects of the present invention is to provide an improved drill which is so constructed and designed as to permit of its operation in inaccessible 10 places and at a point where the ordinary form of ratchet drill could not be used due to the inability to rock or swing the operating handle.

The invention furthermore comprehends 15 in a drill of the character set forth, an improved feeding means for automatically advancing the drill toward the work, which means is capable of being rendered active or inactive at the will of the operator.

The invention furthermore contemplates 20 a drill equipped with a feeding mechanism, which feeding mechanism upon retrograde movement after the drilling operation, may be employed as a means for ejecting the 25 drill bit from the holder.

Other objects reside in the features of 30 simplicity of construction, economy of production and efficiency of operation.

With the above recited and other objects 35 in view, reference is had to the following description and accompanying drawings in which there is exhibited one example or embodiment of the invention, while the appended claims define the actual scope of the invention.

In the drawings—

Figure 1 is a vertical sectional view 40 through a drill constructed in accordance with the invention and illustrating the same in operative use;

Fig. 2 is a plan view thereof;

Fig. 3 is a fragmentary horizontal sectional view taken approximately on the line 3—3 of Fig. 1;

Fig. 4 is a transverse sectional view taken 45 approximately on the line 4—4 of Fig. 2, and illustrating the position of parts when the feeding mechanism is active;

Fig. 5 is a similar view illustrating the 50 position of parts when the feeding mechanism is inactive.

Referring to the drawings by characters of reference, 10 designates a hollow cylindrical drill head or body which has secured

to its opposite ends, caps 11 and 12 detachably associated therewith and formed, respectively, with bearings 13 and 14 which are disposed in axial alinement. The bearing 13 has mounted therein for rotation, a drill bit holder 15 provided with a frusto-conical 55 bore 16 in which the tapered shank 17 of a drill bit 18 is adapted to be received. The upper or innermost end of the bit holder is provided with a beveled pinion 19 which also serves as a shoulder for limiting downward or axial movement of the holder in the bearing 13, while the lower end of the holder 15 is provided with a reduced exteriorly threaded extension 20 for the reception of a nut 21 which prevents inward or 60 upward axial movement of the holder in the bearing 13. A central opening 22 in the beveled pinion communicates with the bore 16 to receive the reduced tang or terminal 65 23 of the drill bit shank 17 for a purpose to be hereafter set forth.

The drill head or body 10 is provided with a radial or lateral tubular boss 24, which is preferably inclined upwardly and is closed by a cap or closure plug 25 detachably secured thereto and provided with an interiorly threaded axial bore 26 in which a tubular sleeve 27 is threaded and through which a rotary drive shaft 28 extends. The drive shaft 28 at its inner end has secured 70 thereto a beveled gear 29 which meshes with the beveled pinion 19 so that rotation of the drive shaft transmits rotary motion to the drill holder 15 and the drill which is carried thereby.

In order to provide means for feeding the drill head and the drill bit carried thereby toward the work W, a feeding mechanism is employed which includes a jack screw 30 which threadedly engages a sleeve 31 mounted for rotation in the bearing 14. The sleeve is held against axial movement by a nut 32 threaded upon the upper or outer end of the sleeve and engaging the upper or outer end of the bearing 14, and by a gear 33 at the inner or lower end which engages the innermost or lowermost end of the bearing 14. The upper and outer end of the jack screw which projects beyond the sleeve 31 is formed with a head 34 having transverse intersecting apertures 35 and provided with a pointed terminal or spur 36 which is designed to engage with a station-

ary object S in spaced opposing relation to the work W.

In order to render the feeding mechanism automatically operative by the turning of the shaft 28, a tubular stub shaft 37 is mounted within the head for rotation, the stub shaft having a pinion 38 at its upper end engaging the gear 33 and a worm wheel 39 at its lower end engaging a worm gear 40 on the drive shaft 28. In order to mount the stub shaft to permit of shifting movement of the same from an active to an inactive position, or vice versa, to control the feed at the will of the operator, a bearing shaft 41 is journaled in the head 10 on sleeve bearings 42 and 43, with the tubular stub shaft 37 mounted on an eccentric or cam portion 44 of the bearing shaft 41. The upper end of the bearing shaft 41 protrudes upwardly through the head and has attached thereto a crank 45, the manipulating handle 46 of which is hollow to receive a spring-pressed detent 47 which is normally engageable selectively in spaced keeper openings 48 and 49 formed in the head 10. The detent is provided with a knob 50 which permits of the retraction of the same from the keeper opening with which it is engaged, to allow for the shifting of the pinion 38 and worm wheel 39 respectively, into or out of engagement with the gear 33 and worm gear 40.

In use and operation of the drill, the bit 18 is engaged with the work and the pointed terminal 36 of the jack screw head is adjusted to engage with the stationary object S. It is, of course, understood that the jack screw is held against rotation by inserting a rod R through one of the transverse intersecting apertures 35 to engage with a stationary abutment A for this purpose. The rotation of the drive shaft through the beveled pinion and gear connection 29 and 19, rotates the drill holder 15 and drill 18 to accomplish the drilling operation. When the tubular stub shaft 37 is shifted to the position illustrated in Figs. 3 and 4, the worm wheel 39 will be rotated by the worm gear 40 while the pinion 38 which meshes with the gear 33 will rotate the sleeve 31 to feed or advance the tool head 10 and the drill toward the work. It is obvious that in event the feeding exceeds the speed with which the drilling operation is accomplished, the operator by pulling upwardly on the knob 50 and swinging the cam or eccentric portion 44 of the shaft to the position illustrated in Fig. 5, the feeding operation may be discontinued intermittently to coincide with the speed with which the drilling operation is being accomplished.

When the drilling operation is completed, the drill may be retracted from the work by retrograde turning movement of the shaft 28 and this retrograde movement may be continued until the jack screw is advanced

into contact with the tail or terminal 23 of the drill bit shank for loosening and ejecting the drill bit from the drill holder.

What is claimed is:

1. A drill, including a drill head, a bit holder rotatably mounted in the drill head, a rotary drive shaft for rotating the bit holder, and automatic feeding means for advancing the drill holder toward the work, comprising an element having a threaded bore swiveled for rotation in the drill head, a non-rotary threaded member engaging said bore, a stub shaft having eccentric mounting in the drill head, interengaging driving means on the stub shaft and element, and interengaging driving means on the drive shaft and stub shaft, and exteriorly disposed manipulating means for said stub shaft for moving the same to render the feeding means active and inactive. 80

2. A drill, including a drill head, a bit holder rotatably mounted in the drill head, a rotary drive shaft for rotating the bit holder, automatic feeding means for advancing the drill holder toward the work, comprising an element having a threaded bore swiveled for rotation in the drill head, a non-rotary threaded member engaging said bore, a stub shaft having eccentric mounting in the drill head, interengaging driving means on the stub shaft and element and interengaging driving means on the drive shaft and stub shaft, and means for manually turning the eccentrically mounted stub shaft to respectively engage and disengage the driving connections for rendering the feeding means active and inactive at the will of the operator. 95

3. A drill, including a hollow drill head, a bit holder rotatably mounted in the drill head, a rotary drive shaft for rotating the bit holder, and automatic feeding means for advancing the drill head toward the work, comprising a rotary sleeve having a threaded bore, a non-rotary jack screw engaging said bore, a gear on said sleeve, a stub shaft having eccentric mounting in the drill head, a pinion on said shaft engageable with the sleeve gear, a driving connection between the rotary drive shaft and stub shaft, and means for moving the stub shaft to selectively render the driving connection active or inactive. 105

4. A drill, including a hollow drill head, a bit holder rotatably mounted in the drill head, a rotary drive shaft for rotating the bit holder, and automatic feeding means for advancing the drill head toward the work, comprising a rotary sleeve having a threaded bore, a non-rotary jack screw engaging said bore, a gear on said sleeve, a stub shaft having eccentric mounting in the drill head, a pinion on said shaft engageable with the sleeve gear, a driving connection between the rotary drive shaft and stub shaft, and means 130

for moving the stub shaft to selectively render the driving connection active or inactive, said means having a detent for holding said latter means in its shifted position.

5. A drill, including a hollow drill head, a bit holder rotatably mounted in the drill head, provided with a tapered bore and a reduced opening, a drill bit having a tapered shank engageable in the bore and a reduced terminal extending through the reduced opening and protruding beyond the drill holder, a rotary drive shaft having operative connection with the bit holder for rotating the same, and automatic feeding means for advancing the drill head and bit toward the work, comprising a rotary sleeve having a threaded bore, a non-rotary jack screw engaging said bore, and a gear on said sleeve, a stub shaft having eccentric mounting in the drill head, a pinion on said shaft engageable with the sleeve gear, a worm wheel on the stub shaft, a worm gear on the drive shaft engaging said worm wheel, and means for advancing the drill head and bit toward the work, comprising a rotary sleeve having a threaded bore, a non-rotary jack screw engaging said bore, and a gear on said sleeve, a stub shaft having eccentric mounting in the drill head, a pinion on said shaft engageable with the sleeve gear, a worm wheel on the stub shaft, a worm gear on the drive shaft engaging said worm wheel, and means for moving the stub shaft to selectively engage the gears to render the feeding means active and inactive.
- 25 to selectively engage the gears to render the feeding means active and inactive.

6. A drill, including a hollow drill head, a bit holder rotatably mounted in the drill head, provided with a tapered bore and a re-

duced opening, a drill bit having a tapered shank engageable in the bore and a reduced terminal extending through the reduced opening and protruding beyond the drill holder, a rotary drive shaft having operative connection with the bit holder for rotating the same, and automatic feeding means for advancing the drill head and bit toward the work, comprising a rotary sleeve having a threaded bore, a non-rotary jack screw engaging said bore, and a gear on said sleeve, a stub shaft having eccentric mounting in the drill head, a pinion on said shaft engageable with the sleeve gear, a worm wheel on the stub shaft, a worm gear on the drive shaft engaging said worm wheel, and means for moving the stub shaft to selectively engage the gears to render the feeding means active and inactive, the feeding means upon retrograde movement of the drive shaft adapted to effect engagement of the jack screw with the reduced terminal of the drill bit for loosening and ejecting the same. •

Signed at New York in the county of New York and State of New York this 1st day of October, A. D. 1927.

ANDREW J. WIKANDER.
